Maurice Bloch

Patented Nov. 10, 1925.

Des. 68,751

UNITED STATES PATENT OFFICE.

HENRY KATZ, OF NEW YORK, N. Y., ASSIGNOR TO THE FERDINAND STRAUSS CORPORATION, OF NEW YORK, N. Y., A CORPORATION OF NEW YORK.

DESIGN FOR A HARMONICA.

Application filed August 26, 1925. Serial No. 14,594. Term of patent 7 years.

To all whom it may concern:

Be it known that I, HENRY KATZ, a citizen of the United States of America, residing at New York city, New York County, State of New York, have invented a new, original, and ornamental Design for a Harmonica, of which the following is a specification, reference being had to the accompanying drawing, forming part hereof, which illustrates a perspective view of a harmonica showing my new design.

I claim:

The ornamental design for a harmonica as shown.

Signed at New York city, New York, this 22nd day of August, 1925.

HENRY KATZ.
